CLAIM

The ornamental design for a fireplace, as shown and described.

DESCRIPTION

FIG. 1 provides a front right perspective view of a fireplace; FIG. 2 provides a front view thereof; FIG. 3 provides a rear view thereof; FIG. 4 provides a right side view thereof; FIG. 5 provides a left side view thereof; FIG. 6 provides a top view thereof; and, FIG. 7 provides a bottom view thereof.

The broken lines shown in the drawings depict portions of the fireplace that form no part of the claimed design. The unclaimed subject matter on the left and right sides of FIG. 2 is the back panel of the returns.
